UNITED STATES PATENT OFFICE.

MARTIN ITJEN AND GEORGE TONY RAPUZZI, OF SKAGWAY, ALASKA.

HOISTING DEVICE.

Application filed October 22, 1925. Serial No. 64,197.

To all whom it may concern:

Be it known that we, MARTIN ITJEN and GEORGE TONY RAPUZZI, citizens of the United States, residing at Skagway, Alaska, have 5 invented certain new and useful Improvements in Hoisting Devices, of which the following is a specification.

This invention relates to improvements in chain hoists, and has for its principal object to provide a highly novel and simple 10 means for hoisting a load in a step by step manner.

Another important object of the invention is to provide a hoisting device which includes a means for holding the load in a suspended position while the lifting means is actuated or moved upwardly, said holding means being automatically released when the lifting means is disposed in an operative position.

A further object is to provide a hoisting device of the above mentioned character which is simple in construction, inexpensive, strong and durable and further well adapted 25 to the purpose for which it is designed.

Other objects and advantages of the invention will be come apparent during the course of the following description taken in connection with the accompanying drawing.

30 In the accompanying drawing forming a part of this application and in which like numerals designate like parts throughout the same:

Figure 1 is a side elevation of the device 35 embodying our invention showing the manner in which the same is used.

Figure 2 is a detail perspective view of the forward end of the lifting lever, the clevis pivotally suspended therefrom, and 40 the locking link, and

Figure 3 is a detail enlarged perspective of the upper end of the load supporting chain showing the locking link associated therewith.

45 In the drawing, wherein for the purpose of illustration is shown the preferred embodiment of our invention, the numeral 1 designates an elongated lever, the forward end of which is provided with the downwardly disposed claw 2 which is adapted for engagement with the link of a suitable chain 3 which is suspended from a stationary support 4 at its upper end. The purpose of this 50 claw will be hereinafter more fully described.

A substantially U-shaped clevis 5 is piv-

otally suspended from the lever 1 at a point adjacent the claw 2, and to this end there is provided a bolt 6 which extends transversely through the forward portion of 60 the lever and through the upper free ends of the arms of the U-shaped clevis. A suitable wing nut 7 is associated with the threaded end of the bolt in the manner clearly 65 shown in Figure 2.

This clevis extends through an enlarged link 8 which forms the uppermost link of the load supporting chain 9 the latter having a hook 10 associated with the lower end thereof for engagement with the article or object to be lifted or hoisted. An extension in the 70 form of an arm 11 is formed on the upper end of this enlarged link 8 and said extension is disposed between the arms of the U-shaped clevis 5, as clearly shown in Figure 2.

An additional enlarged link 12 has its inner end reduced or restricted to provide a neck portion 13, the purpose of which will be presently apparent. This last mentioned link is termed for the purpose of convenience, a locking link. The locking link is secured to the upper end of the extension or arm 11 in any suitable manner so as to cause the locking link to be disposed at substantially right angles to the enlarged link 8 75 and as is further illustrated in the drawing, the arms or sides of the locking link are disposed in a horizontal plane. The locking link is furthermore offset at the juncture of the neck portion 13 with the main body portion of the link, as illustrated, at 14. This locking link has its neck portion disposed 80 between the arms of the U-shaped clevis 5 and the major portion of said locking link is disposed below the claw 2 formed on the forward end of the elongated lever 1 for cooperation therewith in the manner to be 85 presently described.

In use, the hook, of the load supporting chain 9 is secured to the object to be lifted, 90 in the present instance noted by the letter A, and the free end of the chain 3 extends through the outwardly disposed portion of the link 12. In order to lift the load, the free end of the chain 3 is moved inwardly 95 so as to cause one of the links thereof to be disposed within the neck portion 13, and when in this position the free end of the lever 1 is swung downwardly so as to cause the forward end of the lever having the claw 2 formed thereon to be raised. This will 100 permit the claw to move upwardly on the 105

chain 3 for approximately the distance of two links and by disengaging the link of the chain 3 which is disposed within said portion 13, the load will be raised slightly. 5
5 The chain 3 is again moved inwardly so that the link which is disposed within the enlarged portion of the locking link 12 is moved into the restricted neck portion 14 whereby a load will be supported while the 10 claw is again moved upwardly on the chain so as to take hold of the chain further up and permit the load to again be raised a slight distance.

In this manner, a step by step arrangement is provided for raising a load, and provision of a hoisting device of the above mentioned character will prevent any possibility of the load being accidentally dropped after it has been raised, the means for holding the load in a suspended position while the lifting means is actuated, being readily and easily brought into operative position. 15
20

A device of this character may not only be used as a hoisting device, but may also be used for tightening chains, or as a binder, and we do not wish to limit ourselves to the particular use for which the device is adapted.

While we have shown the preferred embodiment of our invention it is to be understood that minor changes in the size, shape and arrangement of parts may be resorted to without departing from the spirit of the invention and the scope of the appended 30 claims.

Having thus described the invention, what we claim as new is:

1. A hoisting device of the class described comprising a lever, a claw formed on the forward end thereof and adapted for engagement with a chain suspended from a stationary support, a clevis pivotally suspended from the forward portion of the lever, a load supporting chain having its 40 upper end suspended from the clevis, and a 45

locking link having its inner end secured to the uppermost link of said load supporting chain, the free end of the first mentioned chain being adapted to extend through said link, the inner end of the link being provided with a restricted neck portion for cooperation with the link of the first mentioned chain in supporting the load in a suspended position while the claw on the lever is moved upwardly on the first mentioned chain to engage an upper link, said first mentioned chain being adapted to be disengaged from said restricted neck portion when the claw has been moved upwardly to facilitate further raising of the load. 50
55
60

2. A hoisting device of the class described comprising a lever, a chain engaging claw formed on the forward end thereof, a substantially U-shaped clevis having the free ends of the arms thereof pivotally secured to the opposed sides of the forward portion of the lever, a load supporting chain having its uppermost link extending through the crown portion of the clevis, an arm extending upwardly from the upper end of the uppermost link of said load supporting chain, a locking link through which the free end of the last mentioned chain is adapted to extend, the inner end of said locking link being provided with a reduced neck portion for cooperation with a link of the first mentioned chain, the inner end of said locking link being secured to the upper end of said arm, said claw adapted to be moved upwardly on the first mentioned chain when the links of the chain are held in locked engagement with the restricted neck portion of the locking link to permit the claw to engage an upper link and enable the lever to be actuated whereby to further raise the 70 load. 75
